PROTECTIVE HAT OR SIMILAR ARTICLE

Charles C. Snow, 183 N. 1300 W.,
Salt Lake City, Utah 84116

Filed Oct. 6, 1971, Ser. No. 187,219

Term of patent 7 years

Int. Cl. D2—03

U.S. Cl. D2—231

Fig. 1

Fig. 2

Fig. 3

Fig. 4

Fig. 7

Fig. 5

Fig. 6

FIG. 1 is a front perspective view of a protective hat showing my new design;

FIG. 2 is a top plan view thereof;

FIG. 3 is a side elevational view thereof on a reduced scale;

FIG. 4 is a front elevational view;

FIG. 5 is a rear elevational view;

FIG. 6 is a bottom plan view drawn to the scale of FIG. 1.

FIG. 7 is a cross sectional view taken on line 7-7 of FIG. 2.

I claim:

The ornamental design for a protective hat or similar article, as shown and described.
